UNITED STATES PATENT OFFICE

CARLOS B. MIRICK, OF WASHINGTON, DISTRICT OF COLUMBIA

REMOTE CONTROL APPARATUS

Application filed December 3, 1927. Serial No. 237,578.

(GRANTED UNDER THE ACT OF MARCH 3, 1883, AS AMENDED APRIL 30, 1928; 370 O. G. 757)

My invention relates broadly to apparatus for tuning remote controlled radio apparatus and more particularly to that type of apparatus that is used on remote controlled airplanes.

The object of my invention is to produce an apparatus with which it is possible to operate on any one frequency within a given band of frequencies and to shift from one frequency to another as desired.

Further objects of my invention will appear more fully hereinafter as the description of the method and apparatus is developed.

15 My invention consists substantially in the construction combination and arrangement of parts associated therewith or as will be more fully hereinafter set forth as shown by the accompanying drawing and finally 20 pointed out in the appended claims.

Reference is to be had to the accompanying drawing in which numeral 1 represents one of the usual type of radio detectors and amplifiers designated in the drawing as R. D. A.

25 for signals received upon any of the conventional types of antenna 2. The amplified signals operate a master relay 3, one of the usual types of vacuum tube relays, which in turn is connected to the selector mechanism 4.

30 This selector mechanism is of a usual type herein shown with legends upon the drawing and designated with numeral 4. It consists of an armature driven by a motor M, which motor has in conjunction therewith a

35 step lock device of any of the usual types, which allows the motor to move from one position to the next consecutive position and stop as the contacts of the device are closed and opened. In close proximity to the end 40 of the armature there are positioned a plurality of contacts to which are individually connected relays. It is believed that the circuit diagram shown in the drawing suffices for a showing of a standard selector mechanism since therein are used conventional symbols for the different elements incorporated 45 therein. When the necessary distinctive signals are received the various contacts 5 of the selector mechanism operate the different auxiliary circuits that operate the various

controls of the airplane or other device to be remotely controlled.

In the usual type of remote control devices the operation is limited to a certain frequency, and no means has been provided 55 heretofore whereby the receiver will follow the transmitter to a new frequency should it be necessary or desirable to shift the transmitter to another frequency because of interference or other causes. I have accomplished 60 this result by providing an additional set of contacts 30 on the selector mechanism 4, and additional circuits which I will designate as follows: The selector relay circuit, the electromagnetic lock circuit, and the 65 master relay and solenoid circuit.

To accomplish these results I have provided a single tuning control 7 on the amplifier and detector 1 with which engages a gear 8, that is mounted upon a shaft 9 that is provided 70 with a rocker arm 10. Connected with the end of the rocker arm 10 is a connecting rod 11, the other end of which engages a pinion 12 that is mounted upon a gear 13 driven by any of the standard types of spring driven 75 motor 14. In engagement with the gear 13, I have provided an electro-magnetic lock 15 which consists of a solenoid 16 and a pivoted lever 16' one end of which engages the gear 13 and the other end of which is acted upon 80 by the magnetic flux of the solenoid 16.

For the operation of the device I have provided the selector relay circuit which consists of a connection from the source of power 17 to the contact 18 of a relay 19 through the 85 armature 20 and the coil 21 of the relay 19, to a contact 22 of the relay 6 of the selector mechanism 4, through the armature 23 of the relay 6, and the other terminal of the source of power 17.

I have further provided the master relay and solenoid circuit from one terminal of the source of power 17 through one contact 24, through the armature 25 and another contact 26 of the master relay 3, through a coil 27 of the relay 19 and to the other terminal of the source of power 17.

Either of these two circuits operate the armature 20 of the relay 19 depending upon the particular method of operation to be here- 10

inafter described. The armature 20 is in series with the electromagnetic lock circuit which consists of a connection from the source of power 17 through the contacts 28 of the relay 19, through the solenoid 16 of the electromagnetic lock 15 and to the other terminal of the source of power 17.

The operation of the device is as follows. Assume that the armature 25 of the master relay 3 rests against the contact 29, the armature 23 of the relay 6 of the selector mechanism 4 rests against the contact 22, and the armature 20 rests against the stops 31 of the relay 19. With the apparatus in this condition the electromagnetic lock circuit is open and the lever 16' is held away from the wheel 13 by means of the tension exerted by spring 32. The wheel 13 then rotates continuously and shifts the tuning of the receiver back and forth across the entire frequency range of the receiver. The frequency upon which it is desired to operate having been determined, a signal is sent out on this frequency which is received upon the antenna 2. When the receiver 1 comes in tune with this signal, it is transmitted to the master relay 3 and causes the armature 25 to move to contact 26. This movement closes the master relay and solenoid circuit.

The flow of current from the source of power 17 through the armature 25, the contact 26 and the coil 27 of the relay 19 causes the armature 20 to close the contacts 28 and 18. The closing of the contacts 18 locks the armature 19 in this position, for the selector relay circuit is then closed through the contacts 18. The closing of the contacts 28 closes the electromagnetic lock circuit and engages the lever 16' with the wheel 13, locking the tuning mechanism of the receiver 1 at this particular frequency. When the signal above referred to stops, the armature 25 returns to the position shown but the rest of the circuits remain closed and the selector mechanism 4 may then be operated with signals of this frequency.

Should it be desirable to shift the frequency of the signals because of interference or for any other reasons, the distinctive signal for the operation of the relay 6 of the selector mechanism is sent. With this signal the armature 23 of the relay 6 is moved to the contact 30 breaking the selector relay circuit at this point but the contacts 28 are held closed by the master relay and solenoid circuit which is closed by the armature 25 resting against the contact 26. When this signal ceases the armature 25 returns to the contact 29 which opens the master relay and solenoid circuit and the armature 20 drops back against the stops 31. The lever 16' then disengages the wheel 13 due to the tension exerted thereon by the spring 32 and the clock mechanism 14 again begins to tune the receiver back and

forth across the range of frequencies over which it will operate.

A new series of signals is then sent out at the frequency at which it is desired to operate. When the tuning mechanism tunes the receiver 1 to that particular frequency the armature 25 is shifted to the contact 26 and the lever 16' again engages the wheel 13 in the manner above described. By the proper selection of signals in this series the armature 23 may be shifted to the contact 22 of the relay 6 closing the selector relay circuit and locking the armature 20 in the position shown, where operation of the different circuits of the selector mechanism 4 may be accomplished by signals of this newly established frequency.

It will be understood that the above description and accompanying drawing comprehend only the general and preferred embodiment of my invention and that minor detail changes in the construction and arrangement of parts may be made within the scope of the appended claims without sacrificing any of the advantages of my invention.

The invention herein described may be manufactured and used by or for the Government of the United States for governmental purposes without the payment to me of any royalty thereon or therefor.

What I claim is as follows:

1. In a remote control device, including a receiver of electric signals, a master relay and a selector mechanism having a plurality of independently operated relays, the combination of means for continuously tuning the receiver across the band of frequencies over which the receiver will operate; said means consisting of a gear mechanism mechanically engaging the tuning controls of the receiver, and means for driving the gear mechanism; means for interrupting the tuning mechanism at any predetermined frequency; said means consisting of a source of power, an electric circuit including the source of power, the contacts of the master relay and a second relay, and an electromagnetic lock circuit; said circuit including the source of power, the contacts of said last mentioned relay and an electromagnetic lock, said lock engaging the gear mechanism; and means for locking the tuning mechanism in that position, said means consisting of an electric circuit from the source of power, through one set of contacts of one relay of the selector mechanism, a coil and the contacts of the relay in the last mentioned circuit; and the electromagnetic lock circuit.

2. In a remote control device, a radio receiver, means for tuning said receiver over a band of frequencies, interrupting means adapted to be actuated by a received wave for interrupting the tuning at the frequency of the received actuating wave, and means adapted to be actuated by a predetermined

signal of the said received frequency to cause said interrupting means to become inoperative.

3. In a remote control device, a radio receiver, means for continuously tuning said receiver over a band of frequencies, interrupting means adapted to be actuated by a received wave for interrupting the tuning at the frequency of the received actuating wave, and means adapted to be actuated by a predetermined signal of the said received frequency to cause said interrupting means to become inoperative.

4. In a remote control device, a radio receiver, means for continuously tuning said receiver over a band of frequencies, said means consisting of a gear mechanism mechanically engaging the tuning controls of the receiver, interrupting means adapted to be actuated by a received wave for interrupting the tuning at the frequency of the received actuating wave, and means adapted to be actuated by a predetermined signal of the said received frequency to cause said interrupting means to become inoperative.

5. In a remote control device, a radio receiver, means for continuously tuning said receiver over a band of frequencies, interrupting means adapted to be actuated by a received wave for interrupting the tuning at the frequency of the received actuating wave, and means adapted to be actuated by a predetermined signal of the said received frequency to cause said interrupting means to become inoperative, said last mentioned means comprising a selector mechanism and a relay operated by said selector mechanism.

6. In a remote control device, a radio receiver, means for continuously tuning said receiver over a band of frequencies, said means consisting of a gear mechanism mechanically engaging the tuning controls of the receiver, interrupting means adapted to be actuated by a received wave for interrupting the tuning at the frequency of the received actuating wave, and means adapted to be actuated by a predetermined signal of the said received frequency to cause said interrupting means to become inoperative, said last mentioned means comprising a selector mechanism and a relay operated by said selector mechanism.

7. In a remote control device, a radio receiver, means for continuously tuning said receiver over a band of frequencies, interrupting means operated by a solenoid, a source of current included in a circuit for operating said solenoid, a selector circuit, a second solenoid actuated by a received wave for closing said first solenoid circuit to operate said first named solenoid, said second named solenoid, actuated by a predetermined signal in said selector circuit for opening said first mentioned solenoid circuit.

CARLOS B. MIRICK.
